UNITED STATES PATENT OFFICE.

CHARLES C. DUFFY, OF NEWPORT NEWS, VIRGINIA.

DUMPING-CAR.

SPECIFICATION forming part of Letters Patent No. 279,361, dated June 12, 1883.

Application filed November 9, 1882. (No model.)

To all whom it may concern:

Be it known that I, CHARLES C. DUFFY, of Newport News, in the county of Warwick and State of Virginia, have invented a new and 5 useful Improvement in Railway Earth-Cars, of which the following is a full, clear, and exact description, reference being had to the annexed drawing, forming part of this specification.

10 This invention relates to railway-cars for hauling earth for building up and repairing road-beds; and the invention consists of the novel construction hereinafter described and claimed.

15 In the drawing is shown a perspective view of my invention.

The platform A of the car is constructed with a narrow plane portion B at the center, extending from one end to the other, and is 20 divided transversely into three nearly equal parts by the cross-bars C D. Between the bars C D, on opposite sides of the narrow portion B, are arranged large chutes E F, which are to extend down between the front and rear 25 wheels with a lateral inclination. Between the bars C D, respectively, and the ends of the car the plane portion B is made somewhat broader than at the center, and at opposite sides of these broader portions are ar-

30 ranged two small chutes, G H, which are located on opposite sides of the bolsters I J, respectively. The chutes are made small at the ends of the car to prevent their contact with the wheels. The series of chutes on each side 35 of the car are provided with a door, K, which is hinged on a rod, L, and is adapted to close the mouths of the chutes. This door is provided with spring-bolts M, which are adapted to engage automatically with suitable keepers

40 in the projecting ends or bottoms of the chutes, and to the bolts are connected chains N, which are attached to the rod D, which is to be turned with a crank, O, to withdraw the bolts. A

single movement of the said rod will withdraw all the bolts on a side at the same instant, 45 when the weight of the earth in the chutes or pockets will force the door open. Any part of the load of earth that may remain on the plane portion B is to be scooped off into the chutes in the act of unloading the car. For 50 the purpose of holding the doors open in this last operation they may be provided with one or more bars or levers attached to their lower edges on the inside of the large chutes, and these bars may be adapted to engage with 55 suitable catches for holding the doors in a propped position.

If desired, the central portion, B, may be made inclined to opposite sides from a central line in order that the entire load may slide 60 down the chutes when the bolts are released.

Having thus described my invention, what I claim, and desire to secure by Letters Patent, is—

1. A railway-car for hauling earth, &c., 65 having the small chutes G H, located on opposite sides of the bolsters I J, respectively, and the large central chutes, E F, arranged between and supported by the cross-bars C D, combined with the doors K, which are made 70 wide at the center and narrow at the ends to adapt them to close the two series of chutes, substantially as shown and described.

2. The combination, with the car having the two series of large and small chutes, and 75 the doors K, made wide at the center and narrow at the ends, of the rod L, the spring-bolts M, and the chains N, connecting the bolts to the rod, whereby they may be released by winding the chains on the rod, substantially 80 as shown and described.

CHARLES C. DUFFY.
